UNITED STATES PATENT OFFICE.

HENRY M. BARNHART AND EDWARD HUBER, OF MARION, OHIO.

DEVICE FOR LOADING AND UNLOADING CARS.

SPECIFICATION forming part of Letters Patent No. 325,309, dated September 1, 1885.

Application filed July 22, 1885. (No model.)

To all whom it may concern:

Be it known that we, HENRY M. BARNHART and EDWARD HUBER, of Marion, in the county of Marion and State of Ohio, have invented 5 certain new and useful Improvements in Devices for Loading and Unloading Cars; and we do hereby declare the following to be a full, clear, and exact description of the invention, such as will enable others skilled in the art to 10 to which it appertains to make and use the same.

Our invention relates to an improvement in a device for loading and unloading cars, the object of the same being to provide a device whereby a train of platform-cars can be loaded 15 or unloaded by a movable device carried on the cars and adapted to travel from car to car; and with these ends in view our invention consists in the combination, with a train of platform-cars, of a sled or frame mounted on 20 said cars and carrying a crane, and devices connecting the sled and cars, whereby the former can be moved from one end of the train to the other end.

Our invention further consists in the parts 25 and combinations of parts, as will be more fully described, and pointed out in the claims.

In the accompanying drawings, Figure 1 is a view in side elevation showing our improvement applied to a train of platform-cars. Fig. 30 2 is a plan view of the same.

A represents a train of platform-cars, each of which latter is provided on its opposite side edges with the upwardly-projecting guides B, which latter can be provided with rollers or 35 not, as desired, and can be removed from the cars when not needed.

C is a sled or carriage formed of a series of beams or runners, a, connected together by cross-braces a', and provided at one or both 40 ends with the rigid loops D, to which the tackle for sliding the sled from car to car is attached. The sled thus formed is preferably about as wide as the car-platforms, and is provided with the beveled ends, as shown, which 45 permit the sled to slide from one car to another without liability of becoming wedged. This sled rests solidly on the platforms, and is provided on its upper surface with a circular track having a flat surface and a toothed 50 perimeter, on which the crane or derrick frame rests. This frame consists, essentially, of a

base, b, and a top, c, connected together by suitable uprights, d, and braces e.

At one end of the base b is pivotally mounted the boom F, the upper end of which is supported by one or more tie-rods, E. This boom is adapted to carry an excavator, F, or block and tackle for elevating and lowering cross-ties, rails, and other articles. This excavating or hoisting tackle is operated by the rope or 55 chain G, the inner end of which is secured to the windlass H, mounted in bearings secured to the derrick-frame. Alongside of the windlass H is located the windlass H', to which is secured a rope or chain, by which the sled is 60 moved. This rope or chain passes from the windlass upwardly over a pulley, f, thence downwardly in or nearly in a line with the axis of the derrick-frame, and around the pulley g, secured to the sled, then forwardly to a 65 pulley secured to one of the cars, and then rearwardly to the rigid loop on the end of the sled. 70

The windlasses are operated by the engine I, which latter takes steam from the boiler, preferably located on the end of the frame farthest 75 from the derrick. This engine is connected with both windlasses, and the latter are provided with clutch or other mechanism whereby either windlass can be thrown out of engagement with the engine, as necessity demands. 80

The derrick-frame is pivoted to the sled in a vertical line passing through the center of the circular track, and is provided with rollers, which latter rest on the upper smooth surface of the circular track and form bearings for the 85 derrick-frame. This frame is also provided with pinions, which latter engage the teeth on the perimeter of the circular track for the purpose of changing the position of the derrick-frame, so as to bring the derrick from one side 90 of the car to the other. These pinions can be operated by hand-wheels or by the engine. The derrick can also be turned by the engine or by suitable devices operated by hand.

By the above arrangement of parts it will 95 be seen that the sled carrying the derrick can be drawn away from the cars as the latter are loaded, and the cars can be drawn toward the material to be loaded. When unloading, the derrick or crane can be drawn toward the 100 cars to be unloaded.

When the machine is employed for clearing

the side of a track or widening cuts alongside of a railroad - track, an ordinary excavator would be employed, and the material as it is excavated would be dumped on the cars.

5 When the device is employed for loading and unloading other material—such, for instance, as stone, timber, or rails—the excavator would be removed and block and tackle substituted.

It is evident that numerous slight changes 10 might be resorted to without departing from the spirit of our invention; hence we would have it understood that we do not limit ourselves to the exact construction herein shown and described; but,

15 Having fully described our invention, what we claim as new, and desire to secure by Letters Patent, is—

1. In a device for loading and unloading cars, the combination, with a train of platform-cars, of a sled or carriage, a crane or derrick mounted on said sled or carriage, and devices, substantially as described, for moving the sled or carriage.

2. In a device for loading and unloading 25 cars, the combination, with a train of platform-cars and a sled adapted to move on said cars, of a derrick-frame pivoted to the sled, a motor mounted on the sled, and devices connecting the motor and car, whereby the sled

can be moved from one end of the train to the other, substantially as set forth.

3. The combination, with a train of platform-cars, each of which latter is provided with side guides, of a sled adapted to travel over said cars and carrying a crane or derrick, and devices carried by the sled and connected to one of the cars for moving the sled, substantially as set forth.

4. The combination, with a sled or carriage mounted on platform - cars, a derrick-frame 40 pivoted to said sled, and a derrick or crane secured to said frame, of the devices, substantially as described, for moving the sled, substantially as set forth.

5. The combination, with a train of cars 45 having side guides, of a sled or carriage having beveled ends, a derrick secured to said sled, a carriage, and devices, substantially as described, for moving the sled.

In testimony whereof we have signed this 50 specification in the presence of two subscribing witnesses.

HENRY M. BARNHART.
EDWARD HUBER.
